VAPORIZER

Fred C. Hunt, West Englewood, N. J.

Application October 3, 1945, Serial No. 620,110

3 Claims. (Cl. 21—119)

1

This invention relates to vaporizers particularly useful for the treatment of the nasal passages, throat and lungs when affected by colds and otherwise but is also applicable to other uses. The heating is accomplished by passing an electric current between electrodes through the liquid in the main vessel or container. The vapor therefrom is then passed through a smaller vessel or chamber containing the medication, the fumes from which are thereby carried outwardly to effect the treatment.

A serious objection to the common forms of vaporizers is due to the fact that there is a more or less direct passage from the heating vessel to the outside discharge opening; and if the vessel is filled above a certain level with the vaporizing liquid, such as water, or if tilted or jolted in use, there is a discharge of boiling hot water from the outlet instead of vapor. This may cause serious injury to the patient by scalding and the wetting and discoloration of the clothing or bedding. Another objection is that a considerable portion of the vapor passes out from the vessel without coming in contact with the medication and consequently gives ineffective and unsatisfactory results.

An important object of the present invention is to so relate the parts of the apparatus that there is no possibility of scalding hot water being ejected from the vaporizer and thus protects the patient or user from possible injury. Another object is to insure that all the vapor will contact the medication and carry the medication with it, thereby obtaining the most efficient and satisfactory results. A further object is to increase the capacity of a small sized apparatus and permit prolonged use without refilling in special treatments, or permit several usual treatments without refilling. A further object is to obtain convenience and simplicity in refilling the main vessel and in renewing the medication. Another object is to provide a simple form of structure for insuring the disconnection of the apparatus from the electric source before access to the interior of the main vessel can be obtained. These and other objects and advantages will be understood from the following description and accompanying drawings which illustrate a preferred embodiment of the various features of the invention.

Fig. 1 is a perspective side view; Fig. 2 is a vertical section showing a section through one of the electrodes; Fig. 3 is a horizontal section on the line 3—3 of Fig. 2; Fig. 4 is a horizontal section on the line 4—4 of Fig. 2; Fig. 5 is a horizontal section on the line 5—5 of Fig. 2; Fig. 6 is a vertical section on the line 6—6 of Fig. 2; Fig. 7 is a plan view of the insulator at the top of the cover with the attachment plug removed; and Fig. 8 is a vertical section of a modified form of outlet.

2

zontal section on the line 5—5 of Fig. 2; Fig. 6 is a vertical section on the line 6—6 of Fig. 2; Fig. 7 is a plan view of the insulator at the top of the cover with the attachment plug removed; and Fig. 8 is a vertical section of a modified form of outlet.

Referring to Figs. 1 and 2, the main heating or vaporizing vessel 10 of glass is mounted on and embraced by a suitable metal base or frame 11, as shown in Fig. 1. The upper portion of the vessel is of reduced diameter and threaded to receive the top metal cover 12, a gasket 13 being introduced on the inner side of the cover and extending over the top edge of the vessel for providing a seal. The cover is provided with a comparatively large circular opening 14. A cylindrical extension 15 surrounding the opening is fixed to the cover at its lower edge and extends upwardly therefrom. The medication container or chamber 16 is of cylindrical form with a closed lower end and an open upper end. It fits loosely within the tubular extension 15 and is provided at its upper end with an outwardly extending rim 15a which engages the top edge of the tube 15 for supporting the chamber in fixed position. The upper portion of the medication chamber is provided with a number of perforations or openings 15b. This chamber is filled with a suitable absorbent material 17 such as absorbent cotton for receiving the medication and in view of the fact that the lower portion of the chamber is not perforated, any excess amount of the medication will be held in the chamber without passing into the main vaporizing vessel. The vapor formed in the heating vessel is forced to pass through the perforations 15b and through the medication held by the absorbent material and passes outwardly at the top of the medication chamber, sufficient space being provided between the chamber and the tube 15 for passage of the vapor between these parts and through the perforations to the absorbent material. The top of the chamber is covered by a converging or tapering outlet cap or nozzle 18 which is provided with a downwardly extending tubular portion 18a which fits closely over the tube 15 with a friction tight fit which enables the user to remove it and replace it. In this manner convenient access is made to the medication chamber for replenishing the medication; also this chamber may be readily lifted for removal in order to replenish the supply of water, or other vaporizing liquid, in the main vessel. Furthermore, this large opening through the cover enables the user to rinse out and keep clean the interior of

the main vessel without the necessity of removing the cover.

It is apparent that when the liquid in the main vessel is heated, the vapor therefrom is forced to pass through the medication chamber and through the absorbent material which insures the effective passage of the vapor through and over the medication thereby effecting efficient conveying of the fumes of the medication out through the nozzle 18 for treatment of the patient. Also by this relationship of parts any possibility of discharge of boiling hot water or other liquid from the main vessel out through the nozzle is avoided because of the necessity of such possible discharge having to pass through the absorbent material which chokes and prevents any such action. This insures protection of the patient from injury by scalding from any discharge of liquid from the main vessel and, of course, prevents the wetting and soiling of clothing and bedding.

The heating of the liquid in the main vessel is accomplished by passing current through and between a pair of carbon electrodes 19 spaced from each other, as shown in Figs. 5 and 6. These electrodes are carried at the lower portion of a vertically extending support 20 of porcelain or other suitable insulating material. This insulator extends from the underside of the cover to near the bottom of the heating vessel. It has two vertically extending holes through which two conducting rods 21 respectively pass freely. At their lower ends they engage the carbons 19 respectively with a forced fit which holds the carbons in fixed position. The insulator is open at its lower end and contains the spaced carbon electrodes 19 as shown in Fig. 6. An open space 22 is provided in the insulator above the space between the carbons as shown in Figs. 4 and 6. The open space 22 communicates at its upper portion with side outlet openings 23 in the insulator as shown in Figs. 2 and 3. Thus a free circulation of the liquid is provided as heated by the passage of the current between the carbons from between the carbons to the space 22 and then out through the side openings 23.

On the outside of the cover 12 of the vessel and opposite the upper end of the insulator 20 is an insulating block 24 of porcelain or other insulating material. This is provided with two circular downwardly extending portions 24a which pass through openings in the cover and engage a corresponding pair of recesses in the upper end of the main insulator 20. The conducting rods 21 pass through openings in the insulating block 24 and extend above this insulator. The upper ends of these rods are threaded and respectively receive threaded sleeves 25 forming terminals for the reception of an attachment plug 26. The lower ends of these sleeves engage the top of the block 24 and thereby draw the carbons, the main insulator 20 and the insulating block 24 firmly together for holding the parts in fixed position on the supporting cover. The attachment plug 26 of the usual type is provided to engage the terminal sleeves 25 for supplying the heating current to the electrodes.

A handle element 27 in the form of a strip of sheet-metal is secured at its lower end to the embracing support 11 and its upper portion is bent to cause the end of the strip to pass into a space 24b formed at one side of the block 24 just above the cover. The block 24 is countersunk on its upper face opposite the space 24b for the reception of a screw 28 which passes

downwardly and engages a threaded opening in the end of the handle connecting element 27 which secures the handle in fixed position. It is obvious that by removing the screw 28 the upper end of the handle is released and may be drawn outwardly by bending the sheet metal strip which permits the top 12 to be removed from the main vessel for inspection or repairs. The attachment plug 26 is enlarged at the sides and when in place covers the screw 28 as shown in Fig. 2. It then necessitates the removal of the attachment plug before access to the screw and to the interior of the vessel is accomplished. It thus insures the disconnection of the device from the source of electricity before the cover is removable and the interior made accessible. However, access to the interior by the user is not always necessary owing to the fact that the medication may be replenished without removing the cover and the main vessel may be refilled and rinsed through the opening 14 in the cover; and it is unnecessary to insure the removal of the attachment plug before removing the cover by the user. Therefore, it is not necessary that the attachment plug cover the screw 28 except for added protection.

Owing to the fact that this improvement prevents any chance of discharge of the heated liquid from the nozzle of the apparatus, as already explained, the main vessel may be nearly filled with the vaporizing liquid instead of being limited to a comparatively low level, and thereby the capacity of the vaporizer is greatly increased and the duration of continuous use with one filling is considerably prolonged, or permits use for several short periods without refilling.

Fig. 8 shows an outlet cap 29 which may be used in place of the outlet nozzle 18 and has a cylindrical lower portion 29a adapted to fit over the tube 15 and an outwardly flaring portion 29b, as distinguished from the converging nozzle 18. The outwardly flaring portion of the outlet shown in Fig. 8 diverges from a small opening at the medication chamber to insure sufficient pressure on the vapor to dispense it over a wide area. The flaring discharge opening of Fig. 8 is advantageous because it enables the medication carried by the vapor to be dispersed over a much larger area than that obtained by the nozzle 18; and in some forms of treatment such wide dispersion of the vapor carrying fumes is particularly helpful.

Instead of heating the vaporizing liquid electrically in the manner shown, it may be otherwise electrically heated or may be heated by other means.

Although a particular embodiment of this invention has been shown and described, it will be understood that various modifications may be made without departing from the scope of the invention.

I claim:

1. A vaporizer comprising a vessel for containing the liquid to be vaporized, a supporting frame for the vessel, a cover for the vessel, electrodes within the vessel spaced apart from each other, conductors connected respectively to said electrodes, an insulating block fixed on the cover, terminals on said block for reception of an attachment plug, said terminals being in electrical connection with said conductors respectively, and mechanical connecting means extending between the frame and said block, said connecting means being removably connected to said block, said connecting means preventing removal of the cov-

er from the vessel until after the disconnection of said removable connection.

2. A vaporizer comprising a vessel for containing the liquid to be vaporized, a supporting frame for the vessel, a cover for the vessel, electrodes within the vessel spaced apart from each other, conductors connected respectively to said electrodes, an insulating block fixed on the cover, terminals on said block for reception of an attachment plug, said terminals being in electrical connection with said conductors respectively, and mechanical connecting means extending between the frame and said block, said connecting means being removably connected to said block, said connecting means preventing removal of the cover from the vessel until after the disconnection of said removable connection, said removable connection being located to be covered by said attachment plug when in place for preventing disconnection of said removable connection until after the removal of said attachment plug.

3. A vaporizer comprising a main vessel for containing the liquid to be vaporized, a supporting frame for the vessel, a cover on top of the vessel, said cover having an opening, a removable container projecting within said opening for containing medication, the bottom of said container and the lower portion of its wall being closed and the upper portion of the wall having perforations

for permitting the passage of vapor from said liquid into and through said container, electrodes within the vessel spaced apart from each other, conductors connected respectively to said electrodes, an insulating block fixed on the cover, terminals on said block for reception of an attachment block, said terminals being in electrical connection with said conductors respectively, and mechanical connecting means extending between said frame and said block, said connecting means being removably connected to said block, said connecting means preventing removal of the cover from the vessel until the disconnection of said removable connection.
